UNITED STATES PATENT OFFICE.

CORNELIUS WEISS, OF BROOKLYN, NEW YORK.

CLOTH-PILEING MACHINE.

957,525.

Specification of Letters Patent. Patented May 10, 1910.

Application filed April 23, 1909. Serial No. 491,753.

To all whom it may concern:

Be it known that I, CORNELIUS WEISS, a citizen of the United States, and resident of Flatbush, borough of Brooklyn, Kings county, New York, have invented certain new and useful Improvements in Cloth-Piling Machines, of which the following is a specification.

This invention relates to cloth piling machines and its novelty consists in the construction and adaptation of the parts as will be more fully hereinafter pointed out.

In Letters Patent of the United States, #937,398, granted to me on the nineteenth day of October, 1909, there is described and claimed a novel form of machine of this class which comprises a table, carriers adapted to be moved along each side thereof, a vertically adjustable bracket secured to each carrier, transverse cloth supporting devices adapted to be supported by the brackets above the table, means for adjusting the brackets at the same height, and other connected and related devices for readily handling cloth in bulk.

The present application relates to improvements upon the machine which forms the subject matter of the application referred to.

In the drawings, Figure 1 is a top plan view of a machine embodying the invention; Fig. 2 is a side elevation thereof; Fig. 3 is an end elevation of the same, the table being shown in transverse vertical section; and Fig. 4 is a perspective detail of the means for upholding the shelves.

In the drawings, 1 is a table having a number of legs or supports 2, along its sides to which are secured rail brackets 50 for the purpose of supporting upper channel rails 5 and lower channel rails 16. The rails 5 and 16 are mounted below the table top in order to leave the edges of the table free, inasmuch as various tools (not shown) such as folding gages, etc., may be secured along the edges of the table if desired. Belts 9 are moved lengthwise of the table by suitable means, as a motor actuated pulley (not shown). The ends of the belts are fastened to carriers 60, one on each side of the table, and each carrier is provided with two lower wheels 62, 62, adapted to roll or travel in the lower channel rails 16 and two similar upper wheels adapted to roll or travel in the upper channel rails 5. The carriers 60 are each

provided on their outer sides with sleeves or boxes 64 to receive the depending stems 61 of brackets 25, and which stems may be vertically adjusted in the sleeves and held in any desired position after adjustment by set screws 66.

Each bracket 25 extends upwardly above the level of the top of the table 1 and is then bent inwardly to form a transverse shelf 250 extending nearly half way across the table 65 and then downwardly again to form a depending flange 251 which is forked and is adapted to fit into a box 640 secured to the side of a smaller carrier 600 supplied with wheels 620 which rest upon the top of the table. A 70 transverse brace 252 is provided to give rigidity to the construction. A turn table 253 is secured to the shelf 250 in any suitable manner, and upon this is mounted the cloth support proper 40. As each support extends 75 practically half way across the table leaving only a small space between them, by the use of this construction, the capacity of the table is practically doubled when relatively narrow lengths of cloth are to be handled. 80

The cloth support comprises first a lower shelf 41 revolvably mounted on the transverse shelf 250 by means of the turn table 253. Uprights 42 are arranged along the edges of the shelf. On their outer side they 85 are each provided with oblique recesses 43 adapted to receive cross bars 44 to the ends of which are pivoted links 440 which, at their opposite ends, are pivoted to blocks 45 which are squared at 450 to rest against the 90 inner vertical side of the upright 42 and at 451 to afford a horizontal surface on which an upper detachable shelf 46 is supported. At suitable places, transverse guide rods 47, 48, are secured to the outer pair of uprights 95 42 on each support. These guide rods may be either permanently or detachably mounted on the uprights in any suitable manner.

In use, the cloth is piled in folds on the shelves 41 and 46 as indicated in dotted outline in Fig. 2 and the loose ends are guided by means of the rods 47 and 48 and are brought together as may be desired. The carriers 60 are propelled by power applied through the belt 9 while the carriers 600 100 105 roll along the table top serve to maintain the cloth support proper in an upright position. As the support can be brought to project beyond the end of the table in either direction the full length of the table may be 110

utilized for the cutting operations. As the cloth supports can be revolved they may be reversed in position and can be caused to travel in the same or opposite directions at 5 the will of the operator, so that the manipulation of the cloth is by the described construction much facilitated.

What I claim as new is:—

1. In a machine of the character described, 10 a table, a rail mounted on each side of and below the top thereof, a carrier movable on the rail on each side of the table, two carriers mounted on the top of the table, and two cloth supports adapted to be moved in 15 parallel lines above the table and each mounted on two carriers, one moving upon the rail alongside of the table and another moving upon the table.
2. A cloth support comprising a revolu- 20 ble lower shelf, uprights secured thereto, an upper shelf, and means for detachably and adjustably securing the upper shelf in position, consisting of detachable blocks supported from the uprights and upon 25 which the upper shelf can rest.
3. A cloth support comprising a revolu- 30 ble lower shelf, uprights secured thereto, an upper shelf, and means for detachably and adjustably securing the upper shelf in posi- 35 tion, consisting of external notches in the uprights arranged in series in substantially horizontal planes and detachable blocks internally supported therefrom and on which the upper shelf can rest.
4. A cloth support comprising a frame- 40 work including a series of uprights, notches cut in the outer side thereof and arranged in series in substantially horizontal planes, detachable blocks each having a horizontal 45 face adapted to serve as a shelf support and a vertical face adapted to rest against the inner side of one of the supports and means engaging with the notches in the uprights to hold the blocks in position.
5. A cloth support comprising a frame- 50 work including a series of uprights, notches cut in the outer side thereof and arranged in series in substantially horizontal planes, detachable blocks each having a horizontal 55 face adapted to serve as a shelf support and a vertical face adapted to rest against the inner side of one of the supports and means engaging with the notches in the uprights to hold the blocks in position, consisting of

rods adapted to rest in the notches and 55 links hinged thereto and to the blocks.

6. The combination of a table, a plurality of frames, each arranged part way across the same so that they can pass each other when moved and carriers arranged in pairs 60 whereby each frame is supported in a horizontal position, one of said carriers being movable on the table and the other alongside of the table.

7. The combination of a table, a plurality 65 of frames, each arranged part way across the same so that they can pass each other when moved and carriers arranged in pairs whereby each frame is supported in a horizontal position, one of said carriers being 70 higher than the other, a cloth support arranged above each frame and a revolving connection between it and the frame.

8. The combination of a table, a frame ar- 75 ranged across the same, carriers by which the frame is supported in a horizontal po- 80 sition, one movable alongside of and another on top of the table, a cloth support ar- 85 ranged above the frame and a revolving connection between it and the frame, the cloth support having a plurality of shelves, one of which is vertically adjustable with respect to the other.

9. The combination of a table, a frame ar- 90 ranged across the same, carriers by which the frame is supported in a horizontal po- 95 sition, one movable alongside of and another on top of the table, a cloth support ar- 100 ranged above the frame and a revolving connection between it and the frame, the cloth support having a plurality of shelves one of which is detachable from the support.

10. The combination of a table, a frame ar- 95 ranged across the same, carriers by which the same is supported in a horizontal posi- 100 tion, one movable alongside of and another on top of the table, a cloth support arranged above the frame and a revolving connection between it and the frame, and a cloth sup- 105 port having a plurality of shelves one of which is detachable from the support and vertically adjustable thereon.

Witness my hand this 21st day of April 1909, at New York, N. Y.

CORNELIUS WEISS.
